DIVISION BLOCK FOR BALING PRESSES

John H. Blakemore, Chicago, Ill.

Application April 2, 1938, Serial No. 199,723

1 Claim. (Cl. 100—24)

This invention relates to division blocks for baling presses. Such blocks are ordinarily made of two series of horizontal planks and intermediate vertical planks, the planks being spiked, bolted or otherwise rigidly attached to each other and the horizontal planks of each series being spaced from each other to provide bale wire grooves. When a division block of this character is dropped into the feed chamber improperly, 10 the plunger strikes it and it is broken at one of the wire grooves, usually the top one. Thus the entire block is broken and the block must be discarded or torn apart and the middle section replaced with new vertically extending boards. 15 Furthermore, there is no way of adjusting this block so that the wire grooves will come evenly spaced for different heights of bales, the variation in the height of bale being due to the loosening or tightening of the baler tension to get the 20 desired weight in the bale.

The general object of my invention is to provide a block which, if it is broken, need not be entirely thrown away but merely requires the two vertical strips which have been broken to be 25 replaced by two others, thus saving time and expense.

Another object is to so connect the vertical strips to the body of the block that they may be adjusted vertically to the body of the block to 30 thus raise the body of the block relative to the bale to bring the grooves in proper position for the wires.

A further object is to provide a structure of this kind comprising an outer layer of horizontal 35 boards, an inner layer of horizontal boards and two intermediate vertical strips, the strips being held in place by interior clamps so that they may be readily taken out or replaced in case of breakage or adjusted.

40 Other objects will appear in the course of the following description.

My invention is illustrated in the accompanying drawing wherein:

Fig. 1 is a view in top plan of a portion broken away of a division block constructed in accordance with an embodiment of my invention;

Fig. 2 is a view in end elevation of the block as illustrated in Fig. 1;

Fig. 3 is a sectional view taken substantially 50 on the line 3—3 of Fig. 1, with portions broken away;

Fig. 4 is a view substantially similar to Fig. 3 but illustrating another embodiment of the invention;

55 Fig. 5 is a fragmentary enlarged sectional view

taken substantially on the line 5—5 of Fig. 4.

As illustrated in Figs. 1, 2 and 3, my divider or division block comprises three sections A, B and C, the section A being at the top. The section A comprises two relatively narrow horizontal boards 1 of desired dimensions and which have interposed therebetween the end spacer members 2 and a central spacer member 3. The boards 1 and members 2 and 3 are maintained in assembled relation by spikes, screws or otherwise, 10 as may be preferred, and as indicated at 4. The holding members 4, which are associated with the central spacing member 3, are also directed through and retain in position the wear blocks 5 housed within an opening 6 extending transversely through the top section A. Interposed between these wear members 5 is a turnbuckle 7 associated in a well-known way with the oppositely threaded shanks 8 carrying the clamping heads 9. Upon turning movement of the buckle 20 or nut 7 in one direction, the shanks 8 will be moved outwardly and caused to have clamping action upon the upper portions of the removable strips 10 which snugly engage within the openings 11 at the opposite sides of the central spacing member 3. These heads 9 are substantially housed within the recesses or pockets 12 provided in the end portions of the spacer member 3.

The section B is constructed substantially the 30 same as the section A, except that the side boards 14 are of a greater width than the side boards 1 and the interposed spacer members 15 extend a slight distance above the upper margins of the boards 14 for contact from below with the spacer 35 members 2 and 3. This results in the provision of the desired upper wire grooves 16. The strips 10 are snugly inserted through the spacers 17 provided between adjacent spacer members 15 and also through the spacers 18 provided between 40 the spacer members 19 of the lower section C. The boards 14 and members 15 of the central section B are maintained in assembled relation through the medium of the spikes or screws 20 or the like, while the spacer members 19 are held 45 to the side boards 21 of the lower section B by the spikes or screws 22 or the like.

The spacer members 19 of the lower section C extend the desired distance above the upper margins of the side boards 21 for contact from 50 below with the spacer members 15 of the section B to provide the wire grooves 23. The central spacer member 19 of the lower section 3 also has disposed transversely therethrough an opening 24 in which are housed the wear members 25 55

through which are directed the shanks 26. These shanks 26 are oppositely threaded into an intermediate turnbuckle or nut 27 and are provided at their outer ends with the clamp heads 28 for holding engagement with the applied strips 10. Upon requisite turning movement of the buckle or nut 27, the clamp members 28 may be operatively engaged with or released from the strips 10.

10 The strips 10 through the coaction therewith of the clamping members 9 and 28 maintain the sections A, B and C in desired assembled relation and, if desired, said sections may be relatively adjusted in order to assure the proper fitting of a block within a bale chamber.

If for any reason the pressure upon the applied block should be excessive, the strips 10 will break at points between the sections A and B and B and C, and under such conditions the sections A and B can be readily removed and new strips 10 applied. This is of advantage because the block as a unit does not have to be thrown away nor torn apart and a new divider made therefrom.

25 The block has its lower corners cut away, as at 29, to make room for any ordinary bunch of hay that may be within the baling chamber and thus materially reducing breakage.

30 While I have previously stated that the sections A and B and C may be relatively adjusted, it is also to be explained that when higher bales are being made and it is necessary to raise the wire groove to place the wires evenly in the bales, the strips 10 can be moved downwardly through 35 the assembled units to cause said strips to project beyond the lower section C as illustrated in Fig. 3 of the drawing, a distance sufficient to raise the block as a unit to the desired height. During this operation, it will be obvious that the 40 clamp members 9 and 28 are released and retightened.

In the embodiment of the invention as illustrated in Figs. 4 and 5, the end spacing members 30 of the top and bottom sections of the block 45 have their inner faces provided with pockets or

recesses 31 in which are substantially housed the clamping members 32. These members 32 are provided with outwardly extending tubular stems 33 in which are engaged the threaded shanks 34. These shanks 34 are swiveled as at 35, to a plate 5 36 extending across an end of a section. The shank 34 outwardly of the plate 36 is provided with an operating head 37. The plate 36 is recessed, as at 38, to house said operating head 37, so that the head will offer no hindrance or obstruction to the proper placement of a block within a bale chamber or in any way interfere with the desired movement of the block within the chamber.

10 It is only necessary to engage a suitable tool 15 with the heads 37 to release the clamp members 32 or engage the same with the holding strips 39 for the sections of the block.

20 Aside from this new placement of the clamping members, the features of the block are substantially the same as comprised in the embodiment of the invention as illustrated in Figs. 1, 2 and 3.

25 What is claimed is:—

A divider block for baling presses comprising a plurality of separable sections adapted to be arranged edge to edge, each of said sections comprising horizontal boards arranged side by side, spacer members between the end and the central portion of the boards, said spacer blocks being 30 spaced apart to provide openings, the openings of one section aligning with the openings of the other sections, holding strips freely insertible through the openings of the sections, clamping members carried by certain of the spacer blocks 35 for contact with the adjacent edge faces of the applied strips and coacting with the opposed walls of the openings for maintaining the sections in assembled relation, and means for moving the clamping members toward or from the strips, the 40 blocks carrying the clamping members having recesses in which said clamping members are substantially fully retracted.

JOHN H. BLAKEMORE. 45
